Ms. 1628

Constant Heedra, of Brooklyn, N.Y.

Assignor to

W. H. Gore & A. Lorenz, of New York, N.Y.

Letters Patent No. 1628 - dated Aug. 12, 1862.

The schedule referred to in these Letters Patent and making part of the same.

To all whom it may concern:

Be it known that I, Constant Heedra, of Brooklyn in the County of Kings, and State of New York, have produced a new and ornamental design for the Base of a Show Base; and I do hereby declare that the following is a full, clear and exact description of the same, reference being had to the accompanying drawings, making a part of this specification in which.

Figure 1, represents a front elevation of my design.

Figure 2, is a transverse vertical section of the same.

Similar letters of reference in both views indicate corresponding parts.

My new design refers to the base of a show case, and it is intended as a modification of that base on which a patent was granted to W. H. Gore, April 26, 1862.

The base A, of my show case B, consists of four members, the lowest of which forms a plinth a, equal in height to about one quarter of the full height of the base. The next succeeding member is a small ovolu b, the vertical height of which is about equal to one quarter the height of the plinth a.

The ovolu b, is surmounted by an ogee c, which forms the principal member of my new base. This ogee occupies about nine sixteenths of the full height of the base, and is placed in an inclined position, as clearly shown in the drawing, so that its actual length is nearly double that of its vertical height, whereby its effect is materially improved. The last and upper member of my new base is an inclined plane d, placed at an angle of about 45 degrees to-

No. 1628

wards the horizon. The vertical height of this member is about three sixteenths of the full height of the base, and it ends with a sharp corner below where it meets the upper end of the ogee C, and above where it forms the upper edge of the base.

If made of sheet metal and highly polished this base produces a beautiful effect.

Having thus fully described my design, what I claim as new and desire to secure by Letters Patent is -

The base A, of a show case B, said base consisting of a plinth a, ovoli b, ogee C, and inclined plane d, as shown and described.

Witnesses.
